UNITED STATES PATENT OFFICE.

OTTO HEINIGKE, OF NEW Utrecht, NEW YORK, ASSIGNOR TO THE
HARTFORD CARPET COMPANY, OF HARTFORD, CONNECTICUT.

DESIGN FOR A CARPET.

SPECIFICATION forming part of **Design No. 19,811**, dated **May 6, 1890.**

Application filed April 11, 1890. Serial No. 347,536. Term of patent $3\frac{1}{2}$ years.

To all whom it may concern:

Be it known that I, OTTO HEINIGKE, a citizen of the United States, and a resident of New Utrecht, Long Island, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is composed of a body A and a border B.

The body A consists of irregular conventionalized leaf forms intersected by a series of lines dividing the leaves into smaller lobes or parts. These leaf forms interlock with each other, the apices of two of them meeting the bases of two others at a common point. This interlocking occurs at regular intervals through the design.

The border B is composed of an inner part similar to the body A and an outer part consisting of a large figure having a heart-shaped form at the center, surmounted by a succession of deeply-serrated leaf forms, the uppermost one having deep serrations. Between and around these large figures are small conventionalized flower forms. The inner margin consists of small conventionalized leaf forms.

What I claim as new, and desire to secure by Letters Patent, is—

1. The design for a carpet, consisting of the body A, substantially as shown.
2. The design for a carpet, consisting of the border B, substantially as shown.
3. The design for a carpet, consisting of the body A and the border B, substantially as shown.

OTTO HEINIGKE.
